OTHER PUBLICATIONS

U.S. Appl. No. 29/383,441, filed on Jan. 18, 2011 and entitled Decorative Element for Lighting Fixtures.

Primary Examiner — Cathron Brooks*Assistant Examiner* — Kevin Rudzinski(74) *Attorney, Agent, or Firm* — McCormick, Paulding & Huber LLP(57) **CLAIM**

The ornamental design for a decorative element for lighting fixtures, substantially as shown and described.

DESCRIPTION

FIG. 1 is a front view of a decorative element for lighting fixtures comprising a new, original and ornamental design, the rear view being a mirror image thereof;

FIG. 2 is a top view of a decorative element for lighting fixtures comprising the new, original and ornamental design; FIG. 3 is a bottom view of a decorative element for lighting fixtures comprising the new, original and ornamental design; FIG. 4 is a left-hand side view of a decorative element for lighting fixtures comprising the new, original and ornamental design; and,

FIG. 5 is a right-hand side view of a decorative element for lighting fixtures comprising the new, original and ornamental design.

The broken lines shown in the drawings illustrate unclaimed portions of the article and form no part of the claimed design.
